UNITED STATES PATENT OFFICE.

JOHN S. HULL, OF BALTIMORE, MARYLAND.

TINNER'S FIRE-POT.

SPECIFICATION forming part of Letters Patent No. 269,577, dated December 26, 1882.

Application filed October 18, 1882. (No model.)

To all whom it may concern:

Be it known that I, JOHN S. HULL, a citizen of the United States, residing at Baltimore, Maryland, have invented new and useful Improvements in Tinner's Fire-Pots, of which the following is a specification.

My invention relates to that class of tinner's fire-pots which are heated by the flame produced by vaporizing gasoline, petroleum, or kindred fluids by means of heat, said fluid being supplied to the burner under pressure by air forced into and compressed in the fluid-supply tank by an air-pump operated by hand or any convenient power; and the points of novelty will be first fully described, and then pointed out in the claims.

In the accompanying drawings, forming part of this specification, Figure 1 is a vertical section through my fire-pot and a burner, a supply-tank and pump being also shown in elevation therein, a portion of the tank being broken away to show a portion of its interior. Fig. 2 is a front elevation of my fire-pot and burner. Fig. 3 is a side elevation of my fire-pot. Fig. 4 is a side elevation and perspective of the grate, and Fig. 5 is a section and an elevation of the deflector.

Like letters refer to the same parts in all the figures.

My fire-pot is composed of two or more globular chambers, which I, for convenience, call "stories," there being two shown in this instance, of which A is the lower and A' the upper one, the latter being supplied at the top with a chimney, A², and the former with an opening in the bottom, leading to the hollow base A³. On one side of the main story A is an opening, a, to receive the end of a retort-tube attached to a burner, and on its opposite side is an opening, a', to admit air to the rear of the deflector B. The bottom opening of this chamber or main story A is partially closed by a grate, C. The fire-pot is composed of two vertical sections, B' B², which are each provided with lugs b², perforated to receive bolts, by which they are fastened together. The base A³ is provided with a box or drawer, a³, to receive any waste solder that may drop from the irons. In the front of each chamber A A',

&c., is an opening, through which the soldering-irons to be heated are introduced.

The deflector B is circular in outline and concavo-convex in section, and is provided with pins b, one at top and one at bottom thereof, which are fitted into half-perforations or semi-cylindrical grooves b' in the sections B' B², which grooves and pins are set at an angle of about forty degrees to the vertical, thus securely holding the deflector in place when the sections are secured together. The deflector is also provided with a semicircular notch on each side to admit of a free circulation of air when in place in the fire-pot.

The burner is composed of substantially a tube, D, having in it a needle, D', adapted to open or close an orifice, D², to admit the vaporized fluid into the retort-tube D³. The retort-tube is perforated, as at d, to admit air and to prevent any palpitating combustion by reason of sudden drafts or gusts of air striking into said openings. They are protected by a hood or outer pipe, D⁴. The joint d' of the burner, being made of copper, is a very good conductor of heat; and in order to keep the back part of the burner as cool as possible the portion d² is made of iron. Below the burner is a cup, d³, to receive a small portion of oil, with which to heat the burner to start the vaporization. It may be utilized also to receive any waste oil which may drip from the burner.

E is the supply-tank, provided with a safety-vent, e, and an air-pump, F. The air being forced from the pump through pipe f into the tank forces the oil up through the pipe e' to the burner. The fluid passing up to the burner under pressure is vaporized in the burner and the vapor lighted in the retort-tube. The air passing into said tube through the openings d intensifies the heat, and the flame passing into the chamber A is thrown back by the deflector B, fills the chamber A, and passes upward, filling the upper chambers.

The soldering-irons to be heated are laid in through the openings in the front of the chambers, and when it is desired to increase the capacity of the fire-pot rods are passed in through openings a⁴, whereby a double layer of irons may be placed in the chamber and heated.

When the irons are in use considerable solder adheres to them and is melted off when they are reheated. This waste has heretofore amounted to a considerable item, and in my device is entirely avoided, the box or drawer a^3 catching all waste solder, which, when it leaves the irons, will drop through the opening in the bottom of the chambers into said box or drawer. The deflector B is kept cool to a certain extent by the air which enters the chamber behind the deflector through the opening a' .

Having thus fully described my invention, what I claim, and desire to secure by Letters Patent, is—

- 15 1. The fire-pot composed of two sections, B' B^2 , united in a vertical plane and bolted together, each section being composed of a base and a series of hemispheres opening into each other, as and for the purpose set forth.
- 20 2. The combination, with the sections B' B^2 , having semi-cylindrical grooves, of the deflector B , having pins b set at an angle, as shown.
- 25 3. The fire-pot consisting of base A^3 and globular chambers A A' , having communicating openings and chimney A^2 , in combination with deflector B and grate-bar C , substantially as set forth.
- 30 4. The fire-pot constructed substantially as described, with globular chambers A A' , having openings in their tops and bottoms, the

base-chamber A^3 , and the receptacle a^3 , whereby waste solder from all the chambers is collected in said receptacle, as set forth.

5. The fire-pot having globular chamber A , the walls thereof having openings a^4 and a 35 door or opening of sufficient vertical dimensions to admit a number of soldering-irons one above the other, for the purpose set forth.

6. The combination, with the fire-pot constructed, as described, with communicating 40 chambers of globular form, of the burner and oil-supply and suitable air-compressing apparatus for forcing the oil into the burner.

7. The combination, with the fire-pot having globular chamber A , the walls thereof being provided with openings a and a' , of the deflector, constructed as described, and the oppositely-located retort-tube, and suitable apparatus for forcing the flame into the chamber against said deflector, as set forth. 45

8. The combination, with the fire-pot having globular chambers A A' and opening a , of the retort-tube inserted in said opening, the burner, a fluid-supply, and suitable air-forcing apparatus, as set forth. 50

In testimony whereof I subscribe my name. 55

JOHN S. HULL.
